UNITED STATES PATENT OFFICE.

EGBERT R. FIELD, OF DETROIT, MICHIGAN, ASSIGNOR TO EUREKA VACUUM CLEANER COMPANY, OF DETROIT, MICHIGAN, A CORPORATION OF MICHIGAN.

DESIGN FOR A FAN.

58,732.

Specification for Design.

Patented Aug. 30, 1921.

Application filed March 12, 1921. Serial No. 451,832. Term of patent 14 years.

To all whom it may concern:

Be it known that I, EGBERT R. FIELD, a citizen of the United States of America, residing at Detroit, in the county of Wayne and State of Michigan, have invented a certain new, original, and ornamental Design for a Fan, of which the following is a specification, reference being had therein to the accompanying drawings, forming part thereof, in which—

Figure 1 is a perspective view of the fan;
Fig. 2 is a front elevation thereof;
Fig. 3 is a central cross section therethrough.

I claim:

The ornamental design for a fan, substantially as shown.

EGBERT R. FIELD.
